William F. Butler & Edward T. B. Rice

Potters Patent

The Schedule is granted to us their Potters Patent and marking for
of the same containing a description in the words of the said William
Butler and Edward T. B. Rice themselves of their improvement
in the method of Casting Boxes for wheels of Carriages.

To all people to whom these presents shall come:—
Take it known that the William Butler, Founder & Edward T. B.
Rice Blacksmith both of Worcester in the County of Worcester &
Commonwealth of Massachusetts have invented a new and useful
improvement in the method of casting Boxes for the wheels of carriages
by means of a hollow iron core & that the following is a full and
exact description of the construction of the same as invented
or improved by us. The many attempts have been made to cast wheel
Boxes in such a way as to have the inside of the Box hard and smooth,
but this fact it is believed, that all efforts to accomplish a desirable
an object have utterly failed. The common method is to cast them
in sand which generally leaves the inside of the Box so rough & uneven
that before the axle tree of a foot in the Box is rimmed or bored out.
And if the iron be hard this method of smelting at smoothing out
and with very considerable expense & to avoid this difficulty, soft
iron is selected for the casting and the result is that the Boxes are
very soon worn out. The object of our improvement is so to cast
the Box that the inside surface of it shall be both hard and smooth.
Instead of making the core which forms the opening or hole thro'
the Box for the axle tree of sand we make use of an iron
tube. The tube may be made of iron in any composition of metals that
will not melt when the molten iron is poured around it. The tube is
large or small according to the size of the box & conical. The one we
have made is of thick sheet iron and the outside surface made smooth.

and plates by being turned in a lathe. This tube is placed in the molten iron box and the pattern put over it and the sand is then injected around the model as in the common method. The pattern is then carefully withdrawn leaving the hollow iron core in its place and the metal poured in. We make use of this tube because when the metal is poured upon it, it becomes greatly heated and expands & being hollow the air is permitted to pass freely through it which cools it quicker than the box itself, or metal becomes cool, and in this way shrinks or contracts faster than the box so that the tube or core when the box is cooled will easily drop out.

If the core were of solid iron it would have received so much heat from the contact with the molten metal that it would have retained the heat longer than the box and the consequence would be that, that the box by its more rapid contraction would either burst or adhere so closely to the core that they could not be separated. It is believed a well ascertained fact that melted iron when poured upon cold iron becomes much harder than when poured upon wood or sand, and as the core we make use of is of iron and made almost perfectly smooth, the inside of the box cast around is very hard and with an even and smooth surface. All we claim as our invention or improvement is the hollow iron core for casting the boxes of the wheels of carriages.
